UNITED STATES PATENT OFFICE

ARTHUR J. HARRIS, OF PATERSON, NEW JERSEY

RIBBON AND THE LIKE ROLL PACK

Application filed August 6, 1928. Serial No. 297,593.

The object of this invention is to provide a neat and attractive pack in which a band of ribbon or other textile material shall be preserved against soiling by handling and also in a compact roll form and at the same time be clearly displayed to the end that the purchaser will have opportunity to select, from among different colors or other qualities of the rolls, some particular color or other quality. To this end the body comprising the roll is contained in a transparent covering, as of transparent paper, which is not simply a single-ply sheet wrapped about the roll and creased or folded to enclose the roll, which involves the difficulty of obtaining uniformity in a run of packs so formed, the necessity in most cases of tying up by cord or carefully performed application of adhesive or pasters and the likelihood of breaking or tearing the enveloping material in or after forming the pack, but which is an envelope having opposite walls bowed apart by said body and exerting pressure on substantially flat ends thereof, thus by keeping said body in a definite relation to the envelope avoiding a condition it is otherwise free to assume or what I term "spilling" of the body, to wit, the displacement laterally of convolutions of the roll or "coning" or "pyramiding" of the roll.

30 In the accompanying drawing,

Fig. 1 is a plan view illustrating one form of the invention;

Fig. 2 is a section on line 2—2, Fig. 1;

Fig. 3 shows in part more or less diagrammatically a modification in which, in place of a ribbon-, braid- or tape-like roll, the roll is of filamentous material, such as sewing twist;

Fig. 4 shows another modified form; and

40 Fig. 5 is a section on line 5—5, Fig. 4;

Let 1 indicate the mentioned body here including a roll formed by winding any band upon itself and having substantially flat ends 1^a and also including a core 2, but the 45 core is not indispensable. The band may be tape, braid, ribbon, etc., or it may be composed of threads 3 lying side by side as in Fig. 3—for instance, sewing twist. Such a roll is susceptible not only of unwinding but 50 as hereinbefore defined. Even if these faults

are in common practice in some measure overcome, so that the rolls are adapted to be handled from the time they are formed until they reach the consumer without deformation, according to the circumstances either 55 the resulting package is unduly expensive, or the material is not protected from soiling or, if it is, its color or other quality is concealed from the purchaser. No existing pack including such a roll is, so far as I know, 60 at once free from a certain expense to prepare, of a nature to protect the contained roll from soiling and from "spilling" and other disturbance, and adapted to reveal its 65 quality clearly to the purchaser.

Wherefore, having such a roll as I have defined, I combine with the same an envelope, as follows:

This envelope 4 may be of any form so that it has opposite side walls 4^a which normally assume the planiform condition and offer some resistance to bowing them from each other, so that with the body 1 contained therein and therefore bowing these walls they would, as shown best in Fig. 2, keep said 70 body in the definite relation illustrated, to wit, with the ends 1^a presented thereto, incidentally preventing the body 1 from 75 "spilling". While I do not wish to be limited to the body having less thickness lengthwise 80 of the axis of winding than it is wide in any diameter (it is here shown circular but that is not indispensable), still that condition will manifestly insure its being maintained in the stated relation to the envelope by said 85 walls thereof. What I mean to define herein by an envelope is a container of more or less flexible stiff sheet material whose two opposite walls, as 4^a 4^a, are connected at opposite margins, as 5 5, in such a way that ingress 90 or egress of the roll at either such margin is prevented; thus, in the example, the envelope is formed of a sheet which is folded at 5 5 to form flaps 6 which are folded toward each other and lapped, as shown, and gummed 95 together where they lap, one of the mentioned walls being formed by the lapped flaps and the other by the opposing part of the material.

A salient object being that while the envelope shall preserve the integrity of the roll 100

and prevent it from being soiled in handling, especially on counters in stores, it shall also afford the purchaser opportunity to inspect the color and other qualities thereof, the envelope according to the invention is composed of transparent sheet material, as paper. In order to reduce the cost of the article to the minimum it will be cheapest to form the whole envelope from a single blank of the 10 transparent material, but so long as one of the mentioned walls is of such material and the purchaser thus has full opportunity to inspect the roll the invention will be accomplished.

15 Various expedients for keeping the body 1 from falling out of the envelopes, as by providing it with flaps 8 and 9 and sealing or otherwise securing said flaps closed, or providing a securing means, as the staple 10, 20 which as shown in Figs. 4 and 5 ties together the two walls 4^a at a point coinciding with the aperture of said body. The latter expedient permits the end of the band to be left protruding from the envelope, as at 11, 25 so that the purchaser can handle such end without separating the said body from the envelope; as shown in Fig. 1 this is also possible by leaving said end, as at 12, protruding from the envelope though flap 9 is gummed 30 down.

One feature involved in my invention is the fact that, whereas the walls 4^a exert pressure on the ends of the body and thereby prevent the mentioned spilling, the envelope 35 also exerts pressure in opposite directions diametrically across said body, thereby preventing unwinding or radial loosening of the band; in the example this latter is due to the walls 4^a converging to points which are 40 in a diameter and on opposite sides of and close to the periphery of said body, for instance, the diameter perpendicular to line 2—2 in Fig. 1.

Further, with respect to that species of 45 my invention in which a body including a band wound upon itself about a central aperture is retained in an envelope (as herein defined) by securing means which ties the walls of the envelope together at a point coinciding with said aperture, whereby said body 50 is protected from handling and may be unwound by a pull on the end of the band with incidental revolution of the body with respect to the envelope, I do not wish to be limited 55 to the envelope in that case being transparent or to the particular form of such a body.

Having thus fully described my invention, what I claim is:

1. As a new article of manufacture, a pack 60 comprising a contained body including a band wound upon itself in the form of a roll, said body having substantially flat ends and being of itself free to spill, and an envelope containing said body and having opposite 65 walls thereof bowed apart by said body and

exerting pressure on said ends and thereby holding said body against spilling and in a definite relation to the envelope, one such wall being transparent.

2. As a new article of manufacture, a pack 70 comprising a contained body including a band wound upon itself in the form of a roll, said body having substantially flat ends and being of less thickness than it is wide on any diameter and being of itself free to spill, and an envelope containing said body and having opposite walls thereof bowed apart by said body and exerting pressure on said ends and thereby holding said body against spilling and in a definite relation to the envelope, 75 one such wall being transparent.

3. As a new article of manufacture, a pack 80 comprising a contained body including a band wound upon itself in the form of a roll, said body having substantially flat ends and being of less thickness than it is wide on any diameter and being of itself free to spill, and an envelope containing said body and having opposite walls thereof bowed apart by said body and exerting pressure on said ends and thereby holding said body against spilling and in a definite relation to the envelope, 85

90

4. As a new article of manufacture, a pack 95 comprising a contained body including a band wound upon itself in the form of a roll, said body having substantially flat ends and being of less thickness than it is wide on any diameter and being of itself free to spill, and an envelope containing said body and having opposite walls thereof bowed apart by said body and converging toward each other to points in a diameter and on opposite sides of and close to the periphery of said body and thereby holding the latter against spilling and in a definite relation to the envelope, 100

105

5. As a new article of manufacture, a pack 110 comprising a contained body including a band wound upon itself in the form of a roll, said body having substantially flat ends and being of itself free to spill and being of less thickness than it is wide on any diameter, and an envelope containing said body and having the opposite walls thereof exerting pressure on said ends and thereby holding 115 said body against spilling and in a definite relation to the envelope, said envelope also exerting pressure in opposite directions diametrically across said body.

6. As a new article of manufacture, a pack 120 comprising a contained body including a band wound upon itself around a central aperture, an envelope containing said body, and means coinciding with the aperture to tie the opposite walls of the envelope together, whereby 125 the body may be unrolled by a pull on the outer end of the band and incidental rotation of said body around said means.

In testimony whereof I affix my signature.

ARTHUR J. HARRIS.
